TYPEWRITING MACHINE

Russell E. Benner, Buffalo, N. Y., assignor to
Remington Typewriter Company, Ilion, N. Y.,
a corporation of New York

Application January 17, 1934, Serial No. 706,995

4 Claims. (Cl. 197—103)

My invention relates to typewriting, computing, and like machines and more particularly to key construction for such machines.

One of the main objects of my invention, generally stated, is to provide simple, inexpensive and effective rubber cushion keys which may be readily attached to key levers or stems and effectively held thereon against accidental detachment.

10 A further object of my invention is to provide rubber cushion keys of the character specified which may be readily applied to and held against accidental displacement from the key levers with the aid of the usual metallic "key rings" by which 15 the key cards are ordinarily held in position in existing machines, and without the necessity of providing special key rings or metallic securing means for holding the rubber keys in place.

20 To the above and other ends which will hereinafter appear my invention consists in the features of construction, arrangements of parts and combinations of devices set forth in the following description and particularly pointed out in the appended claims.

25 In the accompanying drawing wherein like reference characters indicate corresponding parts in the different views—

Fig. 1 is an enlarged detail perspective view of a rubber key constructed in accordance with my invention.

30 Fig. 2 is an enlarged, detail side view partly in section of a modified form of rubber key.

Fig. 3 is an enlarged detail perspective view of a key ring such as is employed in the construction.

35 Fig. 4 is an enlarged vertical section taken through the key cap construction and showing the rubber key attached to a key lever.

40 Considerable difficulty has been encountered heretofore when employing rubber cushion keys in effectively attaching them to the key levers or key stems of the machine so as to prevent the accidental detachment of such keys. Moreover, it has been customary to provide special metallic 45 clamps or fastening means for securing the rubber keys in place, but this is an added expense and has not always proved successful when applying the keys to different machines in the field, and in many cases adds considerably to the height of the keys in the key board.

50 One of the main objects of my invention is to overcome these and other difficulties and provide a simple and inexpensive rubber cushion key so constructed that it may be effectively and readily connected to the key levers with the aid of the ordinary "key rings" by which the "key cards" are ordinarily held in place and without adding unduly to the usual height of the keys in the key board.

55 60 With these ends in view each rubber cushion

key 10 is made with a peripheral groove 11 therein. The upper section and main body portion 12 of the rubber key is made of relatively soft rubber, whereas the lower section 13, or a portion thereof below the circumferential groove 11 is 5 made of relatively hard rubber for purposes which will presently appear. A key ring 14, shown in detail in Fig. 3, is of the usual construction and is similar to that employed in most Remington and other machines on the market. This 10 key ring has an inwardly projecting circular flange 15 ordinarily adapted to bear down on a key card supported on the usual sheet metal key cap 16 riveted to a key lever or stem 17, with the aid of a washer 17*, as indicated at 18. Each key 15 ring is usually secured frictionally to its key cap 16 by a drive fit, though it may be held in place by any other suitable means.

The present construction is such that the comparatively thin, relatively hard, disk-like rubber 20 section 13 is formed integral with the relatively soft body 12 of the rubber key at the bottom thereof and below the circumferential groove 11. For clearness of illustration I have represented the two sections 12 and 13 in Figs. 2 and 4 by 25 different characters of hatch lines. The hard rubber section is, in the present instance, approximately one sixty-fourth of an inch thick and rests on the ledge 19 of the cup-like metal key cap 16. It will be seen, in Fig. 4 for example, 30 that the portion of the rubber key below the circumferential groove 11 is formed partly of soft rubber and partly of hard rubber, with the soft rubber uppermost so that the flange 15 may bear down on said softer part and thereby 35 secure a better gripping action. It will also be observed that the edge of the soft rubber portion upon which the flange 15 bears and grips is parallel to the bottom, hard rubber side of the key, thus affording an easy and firm attachment of 40 the ring 14. In the absence of the relatively hard rubber section 13 each rubber key 10 could not be reliably held against accidental displacement from its key lever. This is especially true in the present instance since but a comparatively small 45 amount of rubber is provided below the circumferential groove 11 and between the points where the hard rubber of the key coats with the ledge 19 and the soft rubber with flange 15. The amount of rubber at this portion of the 50 key, indicated by the distance between the lines *a* and *b* in Fig. 4, in the present instances is approximately one sixteenth of an inch thick and as pointed out above one sixty-fourth of an inch of this is hard rubber. When it is understood that 55 the parts shown in Fig. 4 are drawn on a scale of about six to one with reference to one of the small keys in the key board, the small amount of rubber at this point will be better appreciated. It will be understood, however, that from certain 60

points of view this small amount of rubber beneath the groove 11 is a highly desirable factor in that it enables the rubber key to be held in place by the ordinary key ring 14 and occupies a space 5 no greater than that required for the usual key card. This also aids in providing a rubber cushion key which does not extend to a considerable height above that of the usual keys in the key board.

10 The relatively soft body portion 12 of the rubber key is sufficiently soft to provide a cushion and a resilient soft touch under the action of the operator's fingers thereon and a good gripping surface for the flange 15, and the relatively 15 hard section 13 is sufficiently thin so that it does not materially detract from the cushion effect, especially when it is understood that the rubber key is supported by the key cap 16 only at and near the periphery of the rubber key. The 20 section 13 is of sufficient hardness to prevent the rubber key from being accidentally detached from the key lever but is, nevertheless, not so hard as to prevent the lower portion thereof from being forced through the opening in the 25 key ring and seated beneath the flange 15 thereof, as shown in Fig. 4.

From the foregoing description it will be seen that by the present invention it is unnecessary 30 to provide any special metallic fastening means other than the key rings usually provided on the machine in order to secure the rubber keys in place, and that there is no question of the usual key rings not properly fitting on the key levers of the machine equipped with them and of the 35 rubber keys not being held firmly in place thereby.

The modified form of rubber key shown in Fig. 2 is like that shown in the remaining figures except that there is an increased thickness of 40 relatively hard rubber employed at 20 near its periphery and between the flange 15 and the support 19, which in some instances may be found more desirable and affords a greater security at this point where it is required most. 45 It will be observed that in this form of the invention also, the hard rubber is provided in a layer on the bottom of the soft portion below the circumferential groove 11, thus providing a soft rubber gripping surface for the projecting 50 flange 15 of the key ring 14. Furthermore, even with the increased thickness of hard rubber near the periphery thereof, the lower attaching section maintains its parallel edges to afford an easy and firm attachment of the ring 14.

55 I am aware that heretofore it has been proposed to provide a rubber key with a circumferential groove therein in which a metallic flange is seated to secure the key to the key lever or stem. I do not claim such construction broadly, 60 the effectiveness of the present construction for the purposes set forth depending on a key having a relatively soft rubber portion and a relatively hard rubber integral portion substantially as described above.

65 While I have described in detail two forms of construction embodying my invention and have given dimensions of parts thereof of which I prefer to employ, it should be understood that changes may be made in the construction and in such 70 dimensions without departing from my invention as it is defined in the accompanying claims.

What I claim as new and desire to secure by Letters Patent is:

1. As an article of manufacture, a rubber cushion key having a circumferential groove therein and comprising a relatively soft rubber 5 section with which the finger of the operator contacts and an integral relatively hard rubber section of approximately one sixty-fourth of an inch in thickness located at the bottom of said key, the thickness of the key below said circumferential groove being approximately one sixteenth of an inch and corresponding substantially to the thickness of the usual key card, whereby said rubber key may be effectively secured in place by the usual key ring, the retaining flange 15 of which is positioned within the circumferential groove of said key and grips the soft rubber portion which forms the lower wall of said groove.

2. In a key construction for typewriting and like machines, the combination of a cup-like key cap having a supporting ledge and upstanding circumferential flange thereon, a key ring detachably connected to said flange and having an inwardly extending circular flange, and a rubber cushion key having a circumferential groove 20 therein in which said inturned flange on the key ring may be seated, said cushion key comprising an upper relatively soft rubber section having the circumferential groove therein and an integral lower, circular, relatively hard rubber section, 30 all of the portion of said key below said circumferential groove being seated within the cup-like key cap with the lower hard rubber section bearing near its edge portion only on said supporting ledge and the adjacent soft portion clamped by 35 the flange of the key ring.

3. In a key construction for typewriting and like machines, the combination of a cup-like key cap having a supporting ledge and upstanding circumferential flange thereon, a key ring detachably connected to said flange and having an inwardly extending circular flange, and a rubber cushion key having a circumferential groove 40 therein in which said inturned flange on the key ring may be seated, said cushion key comprising an upper relatively soft rubber section having the circumferential groove therein and an integral lower, circular, relatively hard rubber section, 45 all of the portion of said key below said circumferential groove being seated within the cup-like key cap with the lower hard rubber section there- 50 of bearing near its edge portion only on said sup- porting ledge and the adjacent soft portion clamped by the flange of the key ring, the thick- ness of the relatively hard rubber of the key being 55 greater near the periphery thereof than near the center to provide a greater resistance to the acci- dental detachment of the key.

4. As an article of manufacture, a rubber cushion key comprising an upper relatively thick 60 and soft rubber section, and an integral relatively thin and hard rubber section located below said soft section, said upper section having a circumferential groove therein which divides said key into an upper finger striking portion and a 65 lower attaching portion, the location of said groove being such that said attaching portion has a lower hard layer which provides the required rigidity and an upper soft layer which provides a soft gripping surface for the usual key ring. 70

RUSSELL E. BENNER.
